C. M. F. FRIDEN

CALCULATING MACHINE

Filed June 29, 1925

UNITED STATES PATENT OFFICE.

CARL M. F. FRIDEN, OF OAKLAND, CALIFORNIA.

CALCULATING MACHINE.

Application filed June 29, 1925. Serial No. 40,221.

The invention relates to calculating machines in which the values to be calculated are entered into the machine by the depression of keys. These values are transmitted by the depression of keys, through levers or other mechanism to a value selecting unit. It is essential that the value selecting unit be accurately positioned in its variable settings so that the result produced by the operation of the machine will be correct. Due to the possibility of lost motion between the key and the value selecting unit, said unit may be improperly positioned by the depression of a value key. This lost motion may occur due to wear of coacting parts or due to slight inaccuracies in the dimensions of the cooperating parts.

An object of the present invention is to provide a structure connecting the key with the value selecting unit, which will cause the depression of a value key to set the value selecting unit in correct adjusted position, regardless of slight wear or slight inaccuracies of dimensions of the parts.

Another object of the invention is to provide a value selecting unit positioning lever carrying a rack which is resiliently urged into snug mesh with a gear secured to the value selecting unit, so that there is no lost motion between the rack and the gear, this being the place at which lost motion may otherwise most probably occur.

The invention possesses other advantageous features, some of which with the foregoing will be set forth at length in the following description where I shall outline in full that form of the invention which I have selected for illustration in the drawings accompanying and forming part of the present specification. In said drawings I have shown one form of device for properly positioning the value selecting units, but it is to be understood that I do not limit myself to such form, since the invention, as set forth in the claims, may be embodied in other forms.

Referring to said drawings:

Figure 1 is a vertical longitudinal section through one type of calculating machine, showing the device of my invention in its environment.

Figure 2 is an elevation on a larger scale of the value selecting unit positioning lever, the heads of the screws being removed to show the construction.

Figure 3 is an end elevation of the lever shown in Figure 2, parts thereof being broken away to disclose the construction.

The present invention is particularly applicable to calculating machines of the type disclosed in my Patent No. 1,524,924 issued February 3, 1925. A calculating machine of this character comprises a selecting element 3 which functions during the operation of the machine to cause the counting mechanism 4 to be operated a number of times corresponding to the value represented by the adjusted position of the value selecting units. This unit is moved to selected adjusted position by the depression of one of a series of numeral keys 2, each key corresponding to a different value, from 1 to 9, successively. Depression of the numeral key 2 bearing the numeral designation 9 positions the value selecting unit 3 so that operation of the machine causes the counting mechanism to be moved nine steps. The setting movement is transmitted from the value key to the value selecting unit by a lever 9, with which the key shanks cooperate and a bell-crank lever 6 carrying on its end a rack 7 which meshes with a gear 8 which is secured to the value selecting unit 3.

I have found that in practice lost motion sometimes occurs between the rack 7 and the gear 8, due either to wear of the teeth, or imperfect meshing of the teeth, due to slight inaccuracies in dimensions, so that at times the value selecting unit 3 may not be accurately positioned by the depression of a value key 2, which may result in the introduction of errors into the calculation. In accordance with my invention I have provided means for producing a more positive connection between the lever 6 and the gear 8, so that the value selecting units will always be accurately positioned. In the present instance, this is accomplished by providing means for maintaining the rack 7 in snug meshing engagement with the gear 8, so that lost motion will not occur at this place.

For this purpose one arm of the lever 6 is preferably formed in two parts which are yieldingly urged apart, thus yieldingly pressing the rack 7 into engagement with the gear 8.

The lever arm 12 of the lever 6 is provided with an extension arm 13 which carries the rack 7 and resilient means is inter-

posed between the arms 12 and 13 to urge them apart. The lever arm 12 is provided with two slots 14 and 15 which are preferably in alignment and preferably radially disposed with respect to the rod 16 on which the lever 6 is fulcrumed. Seated in the extension arm 13 are two screws having circular body portions 18 which fit closely in the slots 14 and 15 and having heads 19 overlying the slots to hold the two lever arms 12 and 13 together. The slots are longer than the diameters of the body portion of the screws 17 so that the extension arm 13 has a sliding movement with respect to the lever arm 12, in a direction substantially radial with respect to the rod 16. The two lever arms 12 and 13 are urged apart by a compression spring 21 interposed between an ear 22 on the extension arm 13 and an ear 23 on the lever 6. This spring holds the rack 7 in snug pressure engagement with the gear 8, so that no lost motion occurs between the rack and the gear. Should the teeth of the rack or gear wear due to long continued use, the spring urges the two arms 12 and 13 further apart, causing the teeth on the rack to seat snugly between the teeth on the gear. Further, should there be any slight inaccuracy of dimension in the lever, this inaccuracy is com-

pensated for by the yieldingly extensible arm of the lever.

I claim:

1. The combination with a gear, of a lever having an arm, an extension arm slidably connected to said lever arm, a rack on the extension arm meshing with the gear and a compressed spring interposed between the lever arm and the extension arm to hold the rack in pressure engagement with the gear. 35 40

2. The combination with a gear, of a lever having an arm, an extension arm slidably connected to said lever arm, a rack on the extension arm meshing with the gear, an ear on the lever arm, an ear on the extension 45 arm and a compression spring arranged between said ears to hold the rack in pressure engagement with the gear.

3. The combination with a gear, of an arcuate rack in continuous mesh with said gear and adapted to precisely position said gear, a lever arm comprising two relatively movable parts, one part being fulcrumed and the other part carrying the rack, and resilient means arranged to hold the rack in 50 55 continuous pressure engagement with the gear.

In testimony whereof, I have hereunto set my hand.

CARL M. F. FRIDEN.
